UNITED STATES PATENT OFFICE.

THOMAS L. STURTEVANT, OF FRAMINGHAM, MASSACHUSETTS.

ATTRITION-MILL.

SPECIFICATION forming part of Letters Patent No. 255,550, dated March 28, 1882.

Application filed January 16, 1882. (No model.)

To all whom it may concern:

Be it known that I, THOMAS LEGGETT STURTEVANT, a citizen of the United States, residing at Framingham, in the county of Middlesex and State of Massachusetts, have invented certain new and useful Improvements in Attrition-Mills; and I do hereby declare the following to be a full, clear, and exact description of the invention, such as will enable others skilled in the art to which it appertains to make and use the same, reference being had to the accompanying drawing, and to letters or figures of reference marked thereon, which forms a part of this specification.

The object of this invention is to grind to powder phosphate, grains, ores, or other substances; and it consists, first, in a method of grinding such substances, which consists in compelling one portion of the mass of material to remain stationary, or practically stationary, while another portion revolves, whereby the entire mass itself provides not only its own grinding-surfaces, which are renewed continually, as the flour is removed, but also the material to be ground; second, in a mill for carrying out such method, consisting of a circular recessed wheel or head supported upon a suitable rotary shaft, and combined with a hopper or case for containing the material to be ground and presenting it to the open face of such head, all substantially as herein-after explained.

The drawing accompanying this specification represents a central vertical longitudinal section of a machine embodying my invention.

Reference being had to the above-named drawing, A will be seen to represent a circular head or disk, open or recessed at one end, and at the other secured to one end of a horizontal shaft, B, mounted in a standard or standards, C C, in such manner as to rotate freely in the latter, said shaft being provided with a fast and loose pulley.

Upon the front edge of the chambered head A may be formed an annular lip or ledge, b, the diameter of the mouth of which is less than that of the chamber c of the head, in order to prevent liability of the centrifugal force expelling the contents of such chamber; or this chamber may be frusto-conical in form, with its smallest diameter at the mouth; or it

may be of the form of a bowl with a contracted mouth, for the same purpose. I do not consider these contractions of the chamber b absolutely essential, but prefer to employ some one of them.

D in the accompanying drawing represents a box or case open at top, or a "hopper," as it is usually called, the lower and closed part, d, of this hopper communicating with the chamber c of the head A by an opening, e, preferably of the size of the mouth of the said chamber.

A suction or blast-fan may be employed to extract or expel the flour from the hopper. This may be placed either at the top or bottom, or at any desirable point; and the opening into said hopper is preferably covered by a reticulated screen to prevent the escape of unground particles.

In the use of this mill a considerable quantity of the material to be ground, which is supposed to be in a granular state, or in lumps or blocks, is supplied to the hopper or case D, and the greater part of such hopper, as well as the entire chamber c, filled with such material and the head A put in rapid rotation.

I have found by extended practical tests that the centrifugal force generated by the rotation of the head A tends to maintain the unground material in the chamber c, and the portion thus confined within this chamber rotates by and with the head. I have also found that the mass of material retained within and rotating with the head A constitutes one portion of two grinding-surfaces, the other being supplied by the mass within the hopper, and that the material of these portions becomes reduced to powder by friction between the particles, the powder tending to separate from the agitated mass and escape out through screen g, and the heavier particles to remain in the hopper, the waste of the grinding-surfaces being renewed by the supply constantly furnished to the hopper.

I have shown the recessed head A as arranged to rotate upon a horizontal axis, with the hopper supplying it in front; but the head may be disposed to rotate in a horizontal plane upon a vertical shaft and be fed from the top.

A modified construction of the above mill

would be to employ two rotary recessed wheels arranged upon opposite sides of the hopper and rotating in opposite directions, the hopper having an opening communicating 5 with each.

I propose under some circumstances applying flanges or ribs to the inner periphery of the head A to prevent possibility of movement of the mass of material upon such periphery.

10 I am aware that in attrition-mills an apparatus has been constructed with two wheels revolving in opposite directions. The material is fed through a hopper on each side and falls by gravity into revolving channels 15 formed in said wheels, and by means of radial partitions separating the channels from each other has the velocity of the wheels imparted to it. Owing to this centrifugal force it will tend to advance through said channels and 20 out through the circumferential openings of said channels. When the material has reached this point it meets a similar stream striving to escape through opposite channels in a similar way, and these two streams are pressed and 25 ground against each other by means of the centrifugal force acquired from the revolution of the wheels. My method, although having the same general broad principle of grinding by means of utilizing the material for the 30 grinding-surfaces, has also the principle of having one mass to remain stationary while another mass revolves in a circular head about it. The material, be it of granular or other substance, does the grinding. This broad 35 principle has been shown to be not new in the art; but my method, as hereinbefore described, certainly is an improvement on the process set forth as above. This process is an unreliable one, depending entirely upon the pressure 40 with which the particles are brought together. This pressure, as stated, is derived from the centrifugal force imparted by the wheels. When less velocity is used the force is just so much less, and the pressure of the grain con-

sequently less, and thus the grinding would 45 often be unsatisfactory. There is also danger of the channels becoming clogged by the grain itself. One mass coming one way and another mass striving to reach the same place would tend to mix up and clog the openings. There 50 are no such dangers existing in my apparatus. I cause one mass to remain stationary and constantly supply the other mass which rotates about it in a recessed chamber, the grinding being done by the impact of the rotary 55 solid mass against the stationary solid mass. There are no channels to become clogged, and the pressure of the two masses of material upon each other is always the same, and therefore the material will always be ground satisfactorily. This principle or method of mine will work better, and the apparatus therefore is simpler and consequently less expensive than has hitherto been used in such mills. 60

I claim—

1. The method, substantially as herein described, of grinding various substances, which consists in compelling one portion of the mass of material to be ground to remain in a passive state, while another portion revolves in a compact or coherent body upon it, the intermediate shifting portion being ground by friction or attrition between its own particles, the entire mass itself thus providing not only the grinding-surface, but the material to be ground, 75 and the supply being continuously furnished to the hopper.

2. The mill herein described, consisting of the rotary chambered head, in combination with the hopper arranged to communicate with 80 and supply the chamber of such head, substantially as set forth.

In testimony whereof I affix my signature in presence of two witnesses.

THOMAS LEGGETT STURTEVANT.
